ATTORNEY.

UNITED STATES PATENT OFFICE.

NEWTON R. EVANS, OF RICHMOND, INDIANA, ASSIGNOR TO JOHN A. EVANS, OF RICHMOND, INDIANA.

WINDOW-LIFTER.

No. 899,009.

Specification of Letters Patent. Patented Sept. 15, 1908.

Application filed May 27, 1905. Serial No. 262,605.

To all whom it may concern:

Be it known that I, NEWTON R. EVANS, a citizen of the United States, residing at Richmond, in the county of Wayne and State of Indiana, have invented certain new and useful Improvements in Window-Lifters; and I do hereby declare the following to be a full, clear, and exact description of the invention, such as will enable others skilled in the art to which it appertains to make and use the same.

My invention relates to window, skylight, transom, etc., lifters. Its object is to provide a device for raising or lowering windows, ventilators and similar structures, in which the power may be immediately applied, which shall be composed of parts readily assembled and dismembered, and shall be so simple in construction that any part may be made at small cost, and, therefore, easily replaced in case of breakage.

This invention is, in fact, within the principle of my invention as disclosed in my application No. 250,588, filed March 17, 1905, for a window lifter, in which I have described a window lifter having the power applied through two links to different points of a connecting arm so that I secure a combined pushing and pulling effect. In the form disclosed in this application I have brought the power and the leverage connection into the closest possible union, there being, for example, in my preferred form of construction as illustrated, about an inch of space from the center of the power shaft to the point on the link at which the power is applied. In the device illustrated the link I use is in the form of a hollow rack bar, or rather in the form of a hollow arm, the rack being formed on one side, or attached to one side; and this rack bar engages with a pinion attached to or surrounding the power shaft.

In the drawing, Figure 1 is a side elevation with the operation of the parts indicated, the full lines showing the ventilator closed and the parts inactive; Fig. 2 is a detail showing the links and connecting arm moving to open the ventilator; Fig. 3 is a detail plan view showing power shaft, link and pinion connection, in the fully opened position; Fig. 4 is a detail illustrating the attachment of the connecting arm to an ear on the ventilator or other device to be lifted; Fig. 5 is a detail of a pinion sleeve which is adapted

to be passed over the power shaft and attached to it; Fig. 6 is a detail side elevation of the shaft, the pinion sleeve and the rack-link, the latter being broken away; this figure illustrating, also, the mode of removing the rack-pinion from a link.

In the drawings, 1 represents a beam gable or other suitable supporting means to which the object to be lifted may be hinged. In this case the illustration may be, for example, supposed to represent the ventilator of a greenhouse.

2 represents the frame of the greenhouse and 3 the usual hanger bracket in which the power shaft is journaled, there being, of course, any desired number, depending upon the size of the structure and the number of ventilators, etc.

4 represents a hinged ventilator to be operated by my lifter.

5 is a pipe-shaft journaled in brackets of which 3 is an example. The shaft may have an operating gear or lever at one or both ends, or at any point on the shaft, it being understood that this pipe-shaft is merely one form of operating shaft which may be used for transmitting power. At the point of application of my lifter the shaft is surrounded by a rack-pinion, and I prefer to form this rack-pinion as illustrated by the part 6, which shows two sleeves joined by a number of short rods so that the two sleeves and the rods together form practically a rack-pinion surrounding the power shaft 5. This rack-pinion I preferably cast in a single piece, though, of course, it may be made in any desired manner, it being sufficient that the sleeve is surrounded by a rack-pinion which may be engaged by the racks, to be herein-after described. I preferably also apply on one of the sleeves of the rack-pinion set screws 7, one of which is shown, to secure it in place on the power shaft.

8 and 9 are yoke rack-links, that is, they are links with a yoke or loop at one end and having on the inner face of one side a rack-bar formed either integrally with the loop or yoke or secured thereto by any of the familiar mechanical methods. The rack-link 8 is pivoted at its outer end at 10 to the connecting arm 11, while the rack-link 9 is pivoted at its outer end at the point 12 to the connecting arm 11. In the form illustrated I have preferably made this attachment 12 at the end of the connecting arm 11, but it should

be understood that the precise point of attachment is not essential, providing only that the ends of the rack-links 8 and 9 are attached at different points to the connecting arm 11 it being of course understood that for the best operation of the device the connecting arm should be pivoted to the object to be lifted and to the two links at points on opposite sides of its center. The connecting arm 10 11 is attached at 13 to an ear 14 in the usual manner. At the upper end of each rack-link is an enlargement into which the rack-pinion 6 will fit, so that in applying either one of the links this enlargement 15 may be placed over 15 the rack-pinion, the rack-link then being drawn down and secured in place. The same provision serves as a convenient device for permitting the removal of a link or the pinion at any time.

20 It will be observed that in this construction the racks of the two rack-links or yokes engage the rack-pinion from opposite sides, one being above the rack-pinion and the other below. In use, when power is applied 25 to the shaft 5 it will rotate the rack-pinion 6, and this pinion engaging with the racks of the rack-links 8 and 9 will throw one rack-link in one direction and the other in the opposite direction. That is, it will throw the rack-link 8, when the shaft is turned as indicated in Fig. 1, down and outward, while it will pull the rack yoke 9 in and upward, so that there is applied to the connecting arm 11 a 30 most effective leverage which consists of a 35 combined pulling and pushing effect. The link-racks are crossed, and as these parts move in pushing up the window as indicated in Fig. 1, all the parts in addition to their action in operation, move around as the window 40 goes up until finally the rack-links are crossed in the opposite direction from that in which

they are crossed prior to the lifting operation, as in Figs. 1, 2 and 3. By this construction I secure not only the well-understood direct thrust of a rack and pinion, but I also secure 45 the closest possible application of the power to the link, and I secure at the same time a combined pushing and pulling action upon the connecting arm. That is to say, I secure the equivalent of powerful eccentric action, 50 and I have combined in this device as well as in that of my preceding application a lifting and pulling effect whereby the whole movement of the ventilators is made with a minimum application of power and with no possibility of a dead center. 55

Having fully described my invention what I claim is:—

1. In a window or other lifter, the combination of a power or operating shaft, a pinion on the shaft, rack-links engaging the pinion from opposite sides, and a connecting arm to which the rack-links are pivoted. 60
2. In a window or other lifter, the combination of a power or operating shaft, a pinion borne by the shaft, a pair of crossed rack-links with opposing racks engaging the pinion, and a connecting arm to which the rack-links are attached. 65
3. In a window or other lifter, the combination of a power or operating shaft, yoke-links embracing and engaging the pinion and each having an enlargement at one end through which the pinion may pass, and a connecting arm to which the links are attached. 70

In testimony whereof I affix my signature, in presence of two witnesses.

NEWTON R. EVANS.
